ALLEN & COMPANY LIMITED, OF REDFIELD, ENGLAND, A CORPORATION OF
ENGLAND

CORSET AND THE LIKE

Application filed May 14, 1930, Serial No 452,223, and in Great Britain May 14, 1929.

This invention relates to corsets and similar garments of the kind generally known as "wrap-round" and has for its object to provide an improved construction thereof applicable more particularly to figures in which embonpoint prevails and adapted to afford more effective control in respect to such figures.

According to this invention, the corset or similar garment comprises a body part of ordinary corset material busk sleeves at the front which extend from the top to the bottom of the garment, short busks within the said sleeves extending from the top of the garment to the abdominal region, the said body part being adapted to extend on to the hips of the wearer at the sides and to the bottom of the busks at the front and being connected to the busk sleeves, a central laced insertion in the body part at the back which extends substantially from the small of the wearer's back to the bottom of the garment, the said body part, at the back, extending further down than at the front, an elastic insert in the waist portion of the body part in lapped relation, by its lower end, with the said laced insertion and a plurality of horizontally disposed bands extending around the garment from the top of the said laced insertion to the bottom of the garment and connected to the body part and busk sleeves at the front and the laced insertion at the back.

In constructing corsets and similar garments according to the invention, the body thereof is fitted with a boned central back part which is eyeleted for receiving the lacing and extends from the bottom upwards to a point coincident, or approximately so, with the waist or small part of the back where it is in lapped relation with an insertion of elastic material which completes the said central back part, the side edges of the insertion being secured, by stitching or otherwise, to the said edges of the body which extend to the upper or waist part of the corset or garment. The lower edge of the body is concaved and convexed so as to produce a shaped or wavy curved line which extends from a short distance above the bottom termination of the central back lacing part to the bottom of the

front steels or busks and this portion of the body may be boned or otherwise stiffened as desired or according to the requirements of individual wearers. The material of the hems or sleeves which enclose the steels or busks is extended below the lower front edge of the body and there is attached thereto and to the exterior of the body the horizontally arranged bands, which extend the depth of the lacing at the back and the depth of the busk sleeves at the front, the said bands having a horizontal curved setting with regard to each other and so being of a character adapted to afford a swelling or bulging effect whereby the garment is enabled to fit or lie snugly upon or against the figure.

In order that the invention may be readily understood and carried into effect same will now be more fully described with reference to the accompanying drawings in which:

Figure 1 is a front view of a so-called "wrap-round" corset or garment embodying the present improvements.

Figure 2 is a back view thereof.

a indicates the body part of the corset or garment which carries the front fastening busks *a'* and which has attached thereto, as by the stitching *b'*, the boned central back part *b*. The said central back part is eyeleted as shown for the reception of laces and extends upward approximately to the waist or small part of the back where it laps or overlies an insertion of elastic material such as *c*, the laced opening extending to the bottom of the garment while the elastic material closes the part at the waist above the lacing. The side edges of the elastic insertion are carried by the body part *a* to which they are attached by the sewing indicated at *b'* and *c'*, the lapping of the parts being clearly shown in Figure 2. If desired, the elastic insertion *c* may be supplemented by other elastic insertions (not shown) disposed around the waist part or otherwise of the garment. As will be seen, the body part extends to a short distance above the waist line of the garment and, at the front, is adapted to carry the short busks *a'* where its depth is slightly below the bottoms of the busks while, at the back, its depth is such as to extend to a point about

mid-way between the bottom of the front and the bottom of the garment, the material of the sleeves or the hems a'' a'' which enclose the busks being extended downwards to the bottom of the garment. The lower end of the body part is concaved and convexed, as shown in the illustration so as to enable a shaped or wavy curved edge to be produced with the desired fitting to the figure. The body part may be boned or stiffened as individual wearers may require.

The aforesaid body part a is enclosed by a structure composed of horizontal bands d whereof the ends are attached to the front of the said body at or about the busk hems or sleeves a'' a'' and the fitting for the central back lacing; the said enclosing structure extending downwardly below the body part and upwardly to the top of the central back lacing so as to envelope the abdominal region, the hips and the lower part of the back and the bands composing the same, being cut or fashioned so as to produce a conformation adapted to fit or lie snugly upon or against the figure.

To this end, the horizontal junction edges of the several bands may be of a suitable curvature as will be readily understood by those acquainted with the production of garments of the kind to which the invention relates.

By the improved construction, the garment is rendered capable of ready adjustment about the figure so as to control and retain the same in the condition incidental to such adjustment. The laced insertion b which extends a certain part of the length or depth of the garment is arranged in overlapping relation to the elastic insertion c so that, when donned and the laces manipulated in a manner which will be readily understood, a very effective control of the abdominal region, the hips and the lower part of the back is obtained, the horizontally arranged bands which are adapted to snugly fit over the body and around the figure operating in conjunction with the aforesaid lacing to retain or assist in retaining the said control, thereby adding to the comfort of the wearer. The waist and that part of the figure above the waist are comfortably accommodated by the elastic insertion.

The corset or garment is or may be fitted with the usual suspender device indicated at $e, e.$

I claim:

A corset or similar garment adapted to support the abdominal region of the wearer comprising a body part of ordinary corset material, busk sleeves at the front of the garment extending from the top to the bottom of the garment, short busks within the busk sleeves extending from the top of the garment to the abdominal region, said body part being adapted to extend on to the hips of the wearer at the sides and to the bottom of the busks at the front and being connected to the

busk sleeves, a central laced insertion in the body part at the back extending from substantially the small of the back of the wearer to the bottom of the garment, the said body part extending further down at the back than at the front, an elastic insert in the waist portion of the body part, the lower end of the elastic insert being in lapped relation with said laced insert, and a plurality of horizontally disposed bands extending around the garment from the top of said laced insert to the bottom of the garment and connected to the body part and busk sleeves at the front and the laced insertion at the back.

In testimony whereof I have hereunto subscribed my signature.

JOHN WILLIAM GORDON.
